SCREW-ACTUATED VISE JAW QUICKLY
ADJUSTABLE ALONG RACK GUIDEWAY

Arthur S. Graether, Detroit, Mich.

Application July 31, 1946, Serial No. 687,265

1 Claim. (Cl. 81—28)

1
This invention relates to vises, and in particular to portable vises for use in holding articles during machining operations and the like.

One object is to provide the movable jaw of a vise with a central opening through which an adjusting screw holder extends for engagement with overhanging guideways on the base of the vise, and to provide an inclined screwshaft extending through said holder and engaging an inclined abutment surface on the movable jaw, the movable jaw being provided with forward and rearward portions located respectively forward and rearward of said opening and having depending portions with laterally extending arms engaging the under sides of the overhanging guideways so as to provide firm guidance for the movable jaw, yet be comparatively free from binding by reason of chips falling between the moving parts.

Another object is to provide a vise, as set forth in the preceding objects, wherein the base of the vise is provided with an enlarged groove for the reception of chips, this groove being preferably open at both ends to facilitate the removal of such chips.

Other objects and advantages of the invention will become apparent during the course of the following description of the accompanying drawings, wherein:

Figure 1 is a top plan view of a vise according to a preferred form of the invention;

Figure 2 is a side elevation of the vise shown in Figure 1, partly broken away in central vertical section through the movable jaw;

Figure 3 is a vertical section along the line 3—3 in Figure 2;

Figure 4 is a vertical section along the line 4—4 in Figure 2;

Figure 5 is a vertical section along the line 5—5 in Figure 2, showing the adjusting screw support; and

Figure 6 is a fragmentary front elevation of the screwshaft support shown in Figure 5, as removed from the vise.

Referring to the drawings in detail, Figures 1 to 6 inclusive show a preferred form of the vise of the present invention as consisting generally of a base and fixed jaw unit 10, a movable jaw unit 11, and an adjusting unit 12. These respective units cooperate to form the vise as a whole, and are therefore generally designated by reference numerals and lead arrows.

The base unit 10 consists of a bed 13 having a bottom wall 14 and upwardly extending side walls 15 (Figures 3, 4 and 5) having an elongated

groove 16 between them. Bolted as at 17 to the top surfaces 18 is a pair of inwardly extending guide bars 19 overhanging the groove 16 and provided with ratchet teeth 20 on their undersides.

5 The forward end of the base unit 10 is provided with an upstanding fixed jaw 21 preferably integral therewith and having a recessed generally vertical wall 22 to which a hardened jaw plate 23 is removably secured, as by the bolts 24. The jaw plate 23 is provided with a recessed upper surface 25 extending downwardly to a shoulder 26 for the support of relatively shallow work-pieces and also with a vertical V-groove 27 for the reception of workpieces having curved portions or of circular cross-section, such as collars or shafts. The outer and upper portion of the fixed jaw 21 is inclined as at 28. The bottom wall 14 is provided at intervals with openings 29 for the reception of the point of a drill after 10 passing through the workpiece and also for the escape of chips.

The movable jaw unit 11 consists of a hollow roughly rectangular member with front and rear portions 30 and 31 respectively interconnected

15 by side portions 32, the front portion 30 being higher than the rear portion 31 so that the upper surfaces of the side portions 32 are inclined downwardly from front to rear. The front and rear portions 30 and 31 are provided with narrowed neck portions 33 and 34 respectively (Figures 3 and 4) extending downward between the guide bars 19 and having outwardly extending portions 35 and 36 respectively, the upper surfaces of which engage the lower surfaces of the overhanging portions of the guide bars 19 so as to slide therealong. The ratchet teeth 20 are spaced apart from one another at intervals sufficient to provide flat portions 37 therebetween (Figure 2) for engagement by the

20 flat upper surfaces of the outwardly extending portions 35 and 36. The portions 30, 31 and 32 encircle an approximately rectangular opening 38 (Figure 1) so that the movable jaw unit 11 has the form of a hollow rectangular frame. Thus, the side portions 32 form bridges between the forward and rearward portions 30 and 31, the latter by its relatively great spacing away from the former providing a great leverage which insures smooth sliding action of the movable jaw unit 11 without binding. The forward portion 30 has an inclined rear surface or abutment wall 39 for engagement by the adjustment unit 12 as

25 described below. The forward wall of the movable jaw unit 11 is provided with a recessed surface 40 extending downwardly to a shoulder 41

and cooperating with the corresponding portions 25 and 26 on the jaw plate 23 to receive relatively shallow workpieces.

The adjusting unit 12 includes a roughly I-shaped screwshaft holder 42 (Figures 5 and 6) having an approximately triangular upper portion 43, a narrowed neck portion 44 extending downward between the overhanging portions of the guide bars 19, and outwardly extending lower portions 45 having pawl teeth 46 on their upper edges, the top surface 47 thereof being inclined downwardly and rearwardly (Figure 2) to provide free action of the pawl teeth 46 with the ratchet teeth 20. For the same reason, the upper portion 43 is provided with downwardly inclined lower surfaces 48 terminating in horizontal bottom surfaces 49. The surfaces 47 and 48 are approximately parallel so as to provide, in effect, a passageway therebetween such that when the screwshaft holder 42 is tilted forward, the surfaces 47 and 48 approach parallelism with the upper and lower surfaces of the guide bars 19 so as to permit free sliding movement and at the same time, disengagement of the pawl teeth 46 from the ratchet teeth 20.

The screwshaft holder 42 is provided with an upwardly and rearwardly inclined threaded bore 50 (Figure 2) into which is threaded a correspondingly threaded screwshaft 51 having a hand wheel 52 of relatively large diameter at the rear end thereof and a rounded tip 53 at the forward end engaging the inclined abutment surface 39. The axis of the screwshaft 51 is arranged perpendicular to the abutment surface 39 and the latter is inclined at such an angle to the top surfaces of the guide bars 19 as to provide adequate space between them and the hand wheel 52 for convenient grasp by the fingers, and at the same time enabling the hand wheel 52 to be of sufficiently large diameter to provide a powerful grip for the fingers so as to exert a great mechanical advantage upon the screwshaft 51 for clamping the workpiece between the jaw portions 21 and 30. This is in contrast with the placing of the screwshaft parallel with the bed in prior vises, which gives a cramped position for the fingers, enables the use of only a relatively small hand-wheel, or requires a wrench for adjusting the screwshaft. The fixed jaw portion 28 is provided with a passageway 54 forming an extension of the groove 16 in the base unit 10 (Figure 2).

In the operation of the vise of this invention, the operator grasps the hand wheel 52 as a handle and tilts the screwshaft holder 42 forward to disengage the pawl teeth 46 from the ratchet teeth 20, and, while holding the screwshaft holder 42 in this forward tilted position, pulls it back or pushes it forward so as to move the movable jaw unit 11 forward or backward until the workpiece fits approximately between the jaw portions 21 and 30. If the workpiece is shallow, it is placed between the recessed surfaces 25 and 40 and resting upon the shoulders 26 and 41. If it has a curved portion or is of circular cross-section, it is placed in the vertical V-groove 27 (Figure 1).

When the workpiece has thus been approximately positioned between the fixed and movable jaw portions 21 and 30, the hand wheel 52 is swung downward so as to tilt the screwshaft holder 42 downward and rearward, thereby moving the pawl teeth 46 upward into engagement with the nearest ratchet teeth 20. The operator then rotates the hand wheel 52 and screwshaft 51, thereby causing the movable jaw unit 11 to

move forward and clamp the workpiece tightly between it and the fixed jaw portion 21. The tilted construction of the screwshaft 51, as previously stated, provides for the use of a relatively large handwheel 52 and at the same time adequate space between it and the guide bars 19 so that a powerful grip may be obtained without jamming the fingers. At the same time, this tilted construction enables the forward end 53 of the screwshaft to engage the inclined abutment surface 39 at a height which is relatively close to the guide bars 19, thereby reducing the tendency for the movable jaw unit 11 to bind. The provision of the rear cross portion 31 at a distance relatively remote from the forward portion 30 still further reduces this tendency to bind by giving additional surfaces resting upon the guide bars 19 at a relatively great distance from the supporting surfaces of the forward jaw portion 30. The relatively great longitudinal spacing of these supporting surfaces of the portions 30 and 31 also reduces the distance by which the forward wall 40 of the movable jaw portion will tilt forward when pressure is applied to the screwshaft 51 to clamp the workpiece, since this tilt is very much reduced by the relatively great distance of the rear portion 31 from the forward portion 30, much like a long lever as contrasted with a short lever. In prior vises, lacking this rear portion 31, the relatively short distance between the front and rear surfaces of the movable jaw results in excessive tilting of the movable jaw when pressure is applied by the screwshaft.

The workpiece, thus mounted in the vise, may then be transferred to a machine tool, such as a drill press, shaper, milling machine or the like, and the machining operations performed, either by holding the vise with one hand or by clamping it to the machine table. If drilling is to be performed, the drill may be allowed to pass completely through the workpiece without danger of drilling the vise itself, because of the provision of the openings 29 in the base 14 thereof. The relatively large volume of the groove 16 in the bed 13 enables the reception of a relatively large volume of chips and these may easily be cleaned out by tilting the vise forward and permitting them to drop either through the openings 29 or through the passageway 54 constituting an extension of the groove 16 through the fixed jaw portion 21 (Figure 2).

While I have shown and described my invention in detail, it is to be understood that the same is to be limited only by the appended claim, for many changes may be made without departing from the scope of my invention.

What I claim is:

A vise comprising a longitudinally grooved base having a fixed jaw and a pair of longitudinal guideways overhanging said groove and having longitudinally spaced ratchet teeth on the overhanging portions thereof, a movable jaw slidably mounted on said base for travel along said guideways, a screw shaft support extending downwardly into said groove and having pawl teeth selectively engaging said ratchet teeth, and a clamping screwshaft mounted on said support at an acute angle to said base and engaging an inclined abutment surface on said movable jaw, said movable jaw comprising a hollow frame with a forward work engaging member, a rearward auxiliary supporting member connected thereto and disposed remote therefrom and engaging said guideways, said hollow frame providing an opening through which said clamping screw support

passes downwardly into said groove, said forward and rearward members having depending portions spaced apart from one another and extending downwardly into said groove, and said depending portions having laterally extending arms engaging the under sides of said overhanging guideway portions at spaced locations therealong.
